UNITED STATES PATENT OFFICE.

FREDERICK W. BROCKSIEPER, OF NEW HAVEN, CONNECTICUT, ASSIGNOR TO
SARGENT & CO., OF SAME PLACE.

DESIGN FOR BUTT-HINGE.

Specification forming part of Design No. 5,366, dated November 21, 1871.

To all whom it may concern:

Be it known that I, FREDERICK W. BROCKSIEPER, of New Haven, in the county of New Haven and State of Connecticut, have invented a new and original Design for Butt-Hinge; and I do hereby declare the following, when taken in connection with the accompanying drawing and the letters of reference marked thereon, to be a full, clear, and exact description, and which said drawing constitutes part of this specification and represents a face view of the hinge open.

This invention relates to an improvement in that class of butt-hinges in which the inside or meeting faces are paneled and ornamented; and the invention consists in the peculiar ornamentation of these paneled surfaces, shown in the accompanying illustration and hereafter described.

The edges of each plate are plain, and raised to form a sunk panel, and on this panel tracing is formed of the character known as the "Grecian key," as shown, flush with the edges, and the bed or surface of the panel matted or otherwise finished substantially as shown in the illustration.

I claim—

The design for butt hinge, substantially as shown in the accompanying illustration and described.

F. W. BROCKSIEPER.

Witnesses:

A. J. TIBBITTS,
J. H. SHUMWAY.
